CLAIM

The ornamental design for a compact disc storage container, as described.

DESCRIPTION

FIG. 1 is a perspective view of a compact disc storage container with a closure door in open position;

FIG. 2 is a top plan view thereof with the door in closed position;

FIG. 3 is a front elevational view thereof with the door in closed position;

FIG. 4 is a right side elevational view thereof with the door in closed position, the left side view being a mirror image thereof;

FIG. 5 is a rear elevation thereof with the door in closed position;

FIG. 6 is a bottom plan view thereof with the door in closed position;

FIG. 7 is a top plan view thereof with the door in open position;

FIG. 8 is a front elevational view thereof with the door in open position; and,

FIG. 9 is a right side elevation thereof with the door in open position, the left side being a mirror image thereof.
